UNITED STATES PATENT OFFICE

94,188

DESIGN FOR A RADIATING HEATER CASING

Edward Carstens, Chicago, Ill., assignor to Cole's
Hot Blast Manufacturing Company, Chicago,
Ill.

Application September 12, 1934, Serial No. 53,265

Term of patent 3½ years

To whom it may concern:

Be it known that I, Edward Carstens, a citizen of the United States, and a resident of the city of Chicago, county of Cook, and State of Illinois, have invented a new, original, and ornamental Design for a Radiating Heater Casing, of which the following is the specification, and reference being had to the accompanying drawing, forming a part thereof:

Figure 1 is a perspective of the radiating heater casing of my invention.

Figure 2 is a front elevation of my heater.

Figure 3 is a side elevation of my heater.

I claim:

The ornamental design for a radiating heater casing as shown.

EDWARD CARSTENS.
